INVENTOR:

Maximilian Heller

UNITED STATES PATENT OFFICE

2,581,483

SUSPENDED ASSEMBLY FOR SEATS
OR THE LIKE

Maximilian Heller, London, England

Application April 25, 1946, Serial No. 664,751
In Great Britain June 6, 1945

2 Claims. (Cl. 5—241)

1 The present invention relates to furniture comprising resiliently suspended assemblies in frames for vehicle-seats, chairs, settees, bunks, beds or like articles and one object of the invention is to provide increased comfort by simple and inexpensive means.

According to the invention the furniture assembly comprises a top structure, a downwardly extending spacing member, secured to said top structure, at least two of the bottom edges of said spacing member being spaced inwardly relatively to the edges of said top structure, a support frame, and at least two rows of short tensile springs strung between the lower edges of said spacing member and said support frame, said springs thus holding said top structure in a floating position above the level of said springs, the latter extending below edge portions of said top structure.

The springs are within the area covered by the top structure, and such assemblies are highly resilient in use.

Various embodiments and details of the invention are illustrated by way of example in the accompanying drawings in which

Figure 1 represents a partial perspective view of a bunk according to the invention,

Figure 2 a partial perspective view of a motor-car seat,

Figure 3 a sectional front view of a seat, the frame being indicated in broken lines,

Figure 4 a sectional view of a couch,

Figure 5 is a sectional view of an assembly comprising compression springs,

Figure 6 a diagrammatic view of an assembly, showing in broken lines a seat and back member, and

Figure 7 a partial perspective view of an armrest.

Referring to the drawings, the assembly shown in Figure 1 comprises top structures 1 each of which is provided with two downwardly extending spacing members 2, the bottom edges of the latter being connected by short tensile springs 3 to a support frame 4. The top structures 1 and the spacing members 2 may consist of any sufficiently rigid material such as wood, metal, or artificial resin. The spacing members 2 are spaced inwardly relatively to the edges of the top structures 1 so as to enable the springs to be arranged within the area covered by said top structures. If desired one or more of the edges of the top structures 1 may be in line with or may project beyond the outer edges of the support frame 4. As can be seen from the drawings,

5 the springs 3 are so tensioned as to be substantially horizontal when the furniture assembly is unoccupied. The arrangement of Figure 1, with several independently suspended top structures, has the advantage of providing greater flexibility when in use.

Figure 2 illustrates a motor-car seat comprising a top structure 5 and a spacing member formed of downwardly extending brackets 2 interconnected by bars 6. Tensile springs 3 extend between the bars 6 and a support frame 4, which may also comprise lateral guides for the brackets 2 in order to prevent or limit undesired swaying motion of the part 5.

15 Figure 3 shows an assembly comprising a support frame which is indicated in broken lines and a top structure 7 consisting of a rubber sheet on a metal plate below which is secured a spacing member consisting of a rigid block 8, the underside of which is provided with screw eyes 9 to which the tensile springs are fastened.

20 Figure 4 shows a modification of Figure 1 in which a rigid top structure 1 is provided with upholstery 10. The upper portion of the support frame 4 guides structure 1. A single transverse member 11, interconnecting a plurality of downwardly extending members 2, provides the inner anchorages for the tensile springs 3.

25 Figure 5 illustrates an assembly wherein short compression springs 12 and longer compression springs 13 are so arranged as to form a top structure suspended by short tensile springs 3.

30 Figure 6 shows an assembly in which a spacing member is formed by components 2 and 6. The lower edges of the spacing member are spaced inwardly relatively to the edges of a top structure 1 so that tensile springs 3 can be arranged at all four sides completely within the area covered by the top structure 1, the latter being indicated in broken lines and having an angular projection constituting a back.

35 Figure 7 illustrates an armrest. The vertical front members 14 of a support frame are connected to the rear uprights 13 by means of spaced bars 16, the latter forming guides for a spacing member 17 which consists of a single rigid block.

I claim:

1. A furniture assembly comprising a rigid support frame, a substantially horizontal top structure extending over the area enclosed by said support frame, secured to the underside of said top structure at least one spacing member of substantial length and of comparatively small height and short tensile springs which are substantially horizontal when the furniture assembly

is unoccupied, the inner end of each of said tensile springs being secured to a bottom edge of said spacing member and the outer end of each of said tensile springs being anchored to said support frame, at least two bottom edges of said spacing member being spaced inwardly relatively to the edges of said top structure, the whole arrangement being such that at least two edge portions of said top structure extend over said tensile springs as far as the outer ends of said tensile springs and said top structure is held suspended and moves downwardly on occupation and the tilting movement of said top structure is slight when carrying an occupant's weight off-centre.

2. A furniture assembly comprising a rigid support frame, a substantially horizontal top structure extending over the area enclosed by said support frame, secured to the underside of said top structure at least one spacing member of substantial length and of comparatively small height, and short tensile springs which are substantially horizontal when the furniture assembly is unoccupied, the inner end of each of said tensile springs being secured to a bottom edge of said spacing member and the outer end of each of said tensile springs being anchored to said support frame, at least two bottom edges of said spacing member being spaced inwardly relatively to the edges of said top structure, the whole arrangement being such that at least two edge portions of said top structure extend over

said tensile springs and said top structure is held suspended and moves downwardly on occupation and the tilting movement of said top structure is slight when carrying an occupant's weight off-centre.

MAXIMILIAN HELLER.
